H. MUEGGENBORG

TRAP

Filed Oct. 16, 1922

Fig. 1.

INVENTOR

Henry Mueggenborg

UNITED STATES PATENT OFFICE.

HENRY MUEGGENBORG, OF OKARCHE, OKLAHOMA.

TRAP.

Application filed October 16, 1922. Serial No. 594,919.

To all whom it may concern:

Be it known that I, HENRY MUEGGENBORG, a citizen of the United States, residing at Okarche, in the county of Canadian and

5 State of Oklahoma, have invented a certain new and useful Invention in Traps, of which the following is a specification, reference being had to the accompanying drawings.

This invention relates to an automatically 10 controlled and operable door or lid, adapted intermittently to be unlocked or tripped and likewise turned and locked again, setting the tripping mechanism each period, and the door or lid may be employed for 15 animal traps, garbage or waste receptacles and such other cans or the like, as it may seem desirable to make use of the device.

Primarily the invention is designed for use in connection with animal traps, while 20 the uses to which the same may be put will appear as the matter is further and more definitely explained.

It is an object of the invention to produce a quick action cover or lid, operated at 25 the instance of an automatic trip, and to perpetuate the operation in so far as the mechanism for so doing is kept operative for such service.

Other objects of the invention will appear 30 from a further and more complete reading of the following specification and claims.

On the drawing, accompanying and forming a part of this specification,

35 Figure 1 is a side elevation of my improved trap;

Figure 2 is a detailed perspective of the tripping mechanism, and

40 Figure 3 is an elevational sectional view of the motor used in connection with the invention.

Similar characters of reference indicate similar parts.

If the question of a trap is first to be considered, then the trap proper may be designated by 4, of a mesh character, bordered if desired by a shield 5, having a door 6, and a suitable latch 7.

Mounted upon the upper edge of this mesh structure 4 is a rim 8 to which a motor case 9 is attached, and bearings 10 are also applied.

Operating in these bearings is a shaft 11 applied to a door 12, which in Figure 1 is shown in partial tilted position.

55 To one end of one of the shafts, a pinion 13 is affixed, and which is in mesh with a gear

14 within the motor case 9, and from the shaft 15 of the gear 14, a spring 16 is mounted to actuate the shaft 15 and the gear and pinion, and this spring is wound by a 60 thumb-piece 17.

The shaft 11 is affixed to the lid or door 12 and the said shaft being under the influence of the spring and gears and pinion will cause it to revolve, so long as the spring 65 is under action.

For the purpose of checking the top or lid 12 in a closing or "set" position, levers 18, the ends of which rest in notches 19 of the rim 8 are provided, and these are actuated by springs 20, as the same are mounted in bearings 21. The rear end of each lever 18 is bifurcated at 22 to receive the end 23 of a pivoted platform 24 that has its bearings 25 in a housing 26. This latch construction is placed on a line running through the diameter of the floor 12, so that the latches, two of them, will operate at and from the same point 19, each time the floor 12 makes a one half turn about the central shaft 11. 70 Of course, naturally, in order to allow for this mechanical performance, the latches 18, the springs 20, the platform 24, the housing 26, in fact all that belongs to each latch, must be—one on one side of the floor at one 75 end of the imaginary diametrical line, and the other, on the opposite side or the underside of the floor 12 as can be seen very clearly by reference to Figure 1.

When the platform is pressed upon the 80 end 23 recedes from the bifurcation 22 and the spring 20 draws the lever back and the top or door 12 flops a half turn when the device is set again.

This operation may be repeated indefinitely 95 as long as the motor is in operative position, which can be so maintained by occasional rewinding.

In large apartment houses, each floor is provided with a chute, and garbage and 100 waste are dropped through it to a can below. It often happens that the health law is not complied with, in keeping the can covered, but this trapping arrangement may be used, so that when the weight of the droppings 105 from the chute fall upon the platform or trigger 24 which may be properly shaped as a catch all, then the droppings may be allowed to fall into the can during the semi-revolving of the lid, and the can tightly 110 closed for the next operation.

The several advantages of the invention

will be plain. For instance, the device may be made in such fashion and large enough to be totally submerged until the lid or platform is level with the upper surface, for instance of grain in a granary, and as the mice, rats or other objectionable animals run across the surface and onto the lid or door the trapping will be effective.

The upper part that is applied to a cage 10 as shown in the drawing, may be applied to a barrel, keg, or other specially arranged device. The device, properly arranged may also be formed into and used, when submerged as a fish trap.

15 The modus operandi is as follows:

The floor 12 is pivoted to turn over and over, a half turn at a time, when the latch 18 is released or the same retreats from the notch 19, this retreating or pulling back of 20 the bolt or latch 18 being accomplished by pressure downward by the weight of the rodent on platform 24, this resulting in a trigger-action release of the bolt 18 and, the floor being under the action of the motor to be wound, at will, by 17. One of these latch 25 constructions is on one side of the flopping floor 12, and the other is on the other side thereof, consequently when one latch—for

instance to the left of Figure 1 or that shown in Figure 2 is tripped, it will flop to 30 the position shown to the right of Figure 1 while the one now at the right of Figure 1 jumps to the position shown to the left of Figure 1 and that shown in Figure 2, and so on the repeating operation goes on as 35 long as the rodents attack each platform 24, and as long as the spring action lasts.

Having thus described this invention, I claim:

The trap described, comprising a receptacle with a base, a reticulated portion and a rim, a motor supported by said rim, a centrally-pivoted door, means for revolving said door, a pivoted platform mounted diametrically on said door on opposed sides 45 thereof, a lever mounted in said rim, said lever being bifurcated to receive an end of said platform, said platform being mounted for depression to cause said end to recede from said bifurcation, and a spring acting to 50 draw said lever from said bifurcation and allow the said door to flop a half turn.

Signed at Oklahoma City, in the county and State of Oklahoma this 27th day of September, 1922.

HENRY MUEGGENBORG.
